[57] CLAIM

The design for a mounting for a retractable vehicle cover, as shown and described.

DESCRIPTION

FIG. 1 is an exploded view of a mounting for a retractable vehicle cover showing our new design.

FIG. 2 is an enlarged top plan view thereof;

FIG. 3 is a front elevational view thereof;

FIG. 4 is a bottom plan view thereof;

FIG. 5 is a rear elevational view thereof;

FIG. 6 is a side elevational view the opposite side being a mirror image thereof.
